LIFESAVING NET

William B. Shimp, Columbus, Ohio

Application May 14, 1946, Serial No. 669,593

2 Claims. (Cl. 227—46)

1
My invention relates to a life saving net. It has to do, more particularly, with a life saving net of the type used in fire-fighting which will be held by firemen and into which a person from above can jump in an emergency.

The most common type of life saving net now in use consists of a circular metal frame and a canvas net or disc-shaped section of canvas which is attached to the frame by a series of circumferentially spaced shock absorbers. The frame is usually made in four sections, the adjacent ends of the sections being hinged, and locking means being provided for the hinges. This makes it possible to fold the net into overlapping quarter segments.

One of the objects of my invention is to provide a life saving net which will afford the softest and easiest possible landing for a person jumping into it, thereby lessening danger of injury to such person and to the men who hold the net.

Another object of my invention is to provide a net mechanism in which easiest possible landing is attained by constructing the net mechanism to provide the closest possible approximation of reverse acceleration (deceleration) of a freely falling body so that a body striking the net will immediately meet with minimum resistance to take the initial shock, and, thereafter, with continually increasing resistance until the energy of the falling body is completely neutralized and it comes to rest.

Another object of my invention is to provide a life saving net in which novel cushioning means is provided for cushioning the initial impact of the falling body with the net.

Still another object of my invention is to provide a life saving net of the general type indicated which includes novel and improved shock absorbing units for attaching the canvas net to the frame.

According to my invention, I provide a life net mechanism of the general type indicated and consisting of a circular frame supporting a canvas net by a series of circumferentially spaced shock absorbers. Above the main canvas net or disc I provide an impact cushioning pad which is spaced above the main disc and is secured to the frame by suitable relatively easily yieldable means. Since the pad is spaced above the main disc and is supported by easily yieldable means, it will serve to cushion the initial impact of the falling body before the weight thereof is applied to the main disc. The main canvas disc is supported on the frame by shock absorbers, using

the differential leverage principle which apply the maximum leverage on a spring at the moment of impact and relatively less leverage on the spring in succeeding moments after the impact. Thus, the shock absorbers will offer the least resistance to movement, or fall, of the falling body during the first time unit after impact, and relatively increased resistance to movement in succeeding time units until equilibrium is reached.

The preferred embodiment of my invention is illustrated in the accompanying drawing wherein similar characters of reference designate corresponding parts and wherein:

15 Figure 1 is a plan view, partly broken away, of my life net mechanism.

Figure 2 is a plan view of one of the shock absorbers showing it in normal condition.

Figure 3 is a plan view of the shock absorber showing its condition after a body has fallen into the net and it has been actuated.

Figure 4 is a perspective view of the shock absorber and associated parts.

Figure 5 is a perspective view showing the net in partially folded condition.

Figure 6 is a sectional view taken along line 6—6 of Figure 1.

With reference to the drawing, I have illustrated a life net which comprises mainly, the annular frame 1, a main disc 2 of canvas supported on the frame by means of a plurality of circumferentially spaced shock absorbers 3, and a quilted pad 4 of disc form which is spaced slightly above disc 2 and is attached to the frame 1 by the radially extending circumferentially spaced springs 5.

The frame is made in the usual manner in four arcuate sections. Each section is formed from a tube 6 of annular cross-section and of arcuate outline. The adjacent ends of the tubes 6 are hinged together by a hinge structure 7 which is of the usual self-locking type. Each of the shock absorbers 3 is attached to the frame 1 by means including a collar 8. The collars 8 are held in proper circumferentially spaced relationship by means of spacer tubes 9 which are of the same arcuate outline as the tubes 6 and which slip over such tubes. These spacers 9 are disposed between the adjacent collars 8 and the ends thereof engage such collars and keep them in proper positions circumferentially of the frame. Spacers 9 also serve as non-pinch hand grips.

The edges of discs 2 and 4 are spaced from frame 1. In this space the shock absorbers 3

are disposed. As previously indicated, each of the shock absorbers is formed of mechanism of the differential leverage type. Four lever arms 10 are provided and are disposed substantially in the form of a parallelogram, all of the lever arms being of equal length. The two outer lever arms have their inner ends pivoted between a bifurcated lug 11 which extends inwardly from each collar 8 by means of a pivot pin 12. The outer ends of these outer arms are pivoted by means of the pins 13 to the bifurcated outer ends of cross-heads 14. Similarly, the outer ends of the inner lever arms 10 are pivoted to the opposite ends of the cross-heads 14 by means of the pivot pins 15. The inner ends of the inner lever arms 10 are pivoted by a pivot pin 16 to a bifurcated web attaching member 17. The cross-heads 14 have a rod 18 extending through openings formed therein so that the cross-heads can be moved axially of the rod. The rod is disposed substantially chordal to frame 1 and tangential to the edges of discs 2 and 4. Stop nuts 19 are provided on the ends of the rod 18 for limiting outward movement of the cross-heads on the rod and prevent axial displacement of the rods from the cross-heads. Between the cross-heads 14 in surrounding relationship to the rod 18 is a compression spring 20. This spring normally tends to keep the cross-heads 14 spaced apart in their outermost positions on the rod, as shown in Figures 2 and 4. However, as shown in Figure 3, an inward pull on the member 17 will cause the cross-heads 14 to move towards each other and compress the spring 20.

Each of the members 17 is provided with a loop 21 at its inner side. Through this loop is passed a web or strap 22 which is preferably of leather and extends radially of the canvas disc 2. This web is firmly attached to the canvas disc 2 by means of rivets 23 or other suitable fastening devices. Thus, it will be apparent that the disc 2 is yieldingly attached to the frame 1 by means of the shock absorbers 3.

The quilted pad or disc 4 is attached to the frame 1 in spaced relationship above the disc 2 by means of the springs 5, as previously indicated. The springs 5 are merely comparatively light-tension springs. One end of each spring 5 is anchored to the collar 8 by means of an upstanding lug 24 which is integral with the collar 8. The other end of the spring 5 is anchored to a web attaching member 25. This member 25 has a loop 26 through which a web or strap 27 is passed. The web or strap 27 is preferably of leather and is attached to the pad 4 by rivets 28 or other suitable means.

In the use of this net, it will be held in the usual manner by a crew of men who will grip the spacers 9. The shock absorbers 3 will be in the condition illustrated in Figure 2. When a person jumps into the net, the body will first land on the impact cushioning disc or pads 4. Since this pad is supported by the easily yieldable springs 5, the springs will be quickly stretched and the pad 4 will move down against the disc 2. Thus, the easily yieldable pad will serve to cushion the initial impact of a falling body before the weight thereof is applied to the main disc 2. When the weight is applied to the main disc 2, the shock absorbers 3 will function. Due to the arrangement of the levers 10 of the shock absorbers, being based on the differential leverage principle, a minimum resistance to the compression of the spring 20 is offered by the levers

10 when they are in their initial positions, as shown in Figure 2. As the attaching member 17 is pulled towards the center of the frame 1, this resistance to the compression of the spring 20 is increased. Thus, a maximum of leverage on the springs 20 is applied at impact time and relatively less leverage is applied on the springs in succeeding time units. Consequently, this allows the greatest movement, or fall, of the falling body during the first time unit after impact, and relatively less movement in succeeding time units until equilibrium is reached. This constitutes a close approximation of reverse acceleration of a freely falling body, and an improvement on all previously used life nets.

The net may be folded up in quarter segments in the usual manner, as indicated in Figure 5. The shock absorbers 3 are outside the area of the canvas and facilitate this folding operation. Since the shock absorbers are positioned beyond the canvas and not beneath it there is less danger of the shock absorbers damaging the canvas. Also, since the shock absorbers are disposed close to the frame 1, there is less danger of injury to the person falling into the net. Because of the arrangement of the springs 20 and associated parts of the shock absorbers substantially tangential to the canvas rather than radially, as in prior art devices, longer springs can be used and greater travel of the web or strap attaching devices will be permitted. Consequently, the canvas will be permitted to flex to a greater extent. The shock absorbers are free to shift and adjust themselves to the direction of the force of the impact caused by the body landing offcenter. When the canvas has been relieved of the weight, the shock absorbers will quickly return to their original condition.

The life net which I have provided will provide for the easiest possible landing, inasmuch as a body striking the net meets immediately with minimum resistance and thereafter with continually increasing resistance until the energy of the falling body is completely neutralized and it comes to rest. As a corollary to the above, the body will fall through the maximum distance in the first time unit after striking the net (impact time) and through relatively less distance in each succeeding time unit until equilibrium is reached and the body is at rest. My net will deliver a minimum of shock to (1) the falling body, (2) the men who hold the net, and (3) the net mechanism itself.

Various other advantages will be apparent from the preceding description, the drawing and the following claims.

Having thus described my invention, what I claim is:

1. A life-saving net comprising an annular frame, a net of annular form having its edge spaced from the frame, a plurality of circumferentially spaced shock-absorbing units disposed in said space, anchoring brackets mounted on the frame and anchoring brackets carried by the net for connecting said units to the frame and net, each of said units comprising a rod disposed substantially chordal to the frame, a compression spring surrounding the rod, a pair of cross-heads associated with the rod for movement towards and away from each other and engaged by the spring, a pair of outer levers having their outer ends pivoted to the cross-heads and their inner ends pivoted to each other and to said anchoring bracket mounted on the frame and associated

therewith, a pair of inner levers having their outer ends pivoted to the cross-heads and their inner ends pivoted to each other and to the anchoring bracket connected to the net and associated therewith, an impact cushioning pad of circular outline supported slightly above said net and having its edge spaced from the frame, and means for yieldingly attaching said pad to the frame, said means including radially extending tension springs extending over the associated shock absorbing units, each of said springs having its outer end connected to said anchoring bracket mounted on the frame and its inner end connected to an anchoring bracket attached to said pad.

2. A life saving net according to claim 1 wherein the anchoring brackets on the frame comprise collars surrounding a main frame member and which are held in spaced relationship thereon by means of spacer members surrounding said main frame member. 20
